US0D1108886S

(12) **United States Design Patent** (10) **Patent No.:** **US D1,108,886 S**
(45) **Date of Patent:** **** Jan. 13, 2026**

(54) **GRATE FOR PORTABLE GRILL**

(71) Applicant: **Dometic Sweden AB**, Solna (SE)

(72) Inventors: **Samantha Mays**, Roodepoort (ZA);
Rogier Kappelhoff, Amsterdam (NL);
John Huang, Luoding (CN)

(73) Assignee: **Dometic Sweden AB**, Solna (SE)

(**) Term: **15 Years**

(21) Appl. No.: **29/921,305**

(22) Filed: **Dec. 15, 2023**

(30) **Foreign Application Priority Data**

(57) **CLAIM**

The ornamental design for a grate for portable grill as shown and described.

DESCRIPTION

FIG. 1 is a first perspective view of a grate for portable grill showing the new design;

FIG. 2 is a second perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

1 Claim, 8 Drawing Sheets
